UNITED STATES PATENT OFFICE.

JOHN D. WATSON, OF APPLETON, WISCONSIN.

HEDDLE-FRAME MOVEMENT.

Application filed February 1, 1924. Serial No. 690,019.

To all whom it may concern:

Be it known that I, JOHN D. WATSON, a citizen of the United States, and resident of Appleton, in the county of Outagamie and State of Wisconsin, have invented new and useful Improvements in Heddle-Frame Movements, of which the following is a description, reference being had to the accompanying drawings, which are a part of this specification.

This invention relates to gearing for heddle frames of weaving machinery, and finds particular utility in connection with machines for weaving Fourdrinier wire used in paper making machinery.

In manufacturing Fourdrinier wire cloth, it is absolutely essential that the same be smooth and uniform, as any irregularity in the cloth is reflected in the finish of the manufactured paper. Any irregularity or lack of uniformity in the movement of the heddle frames in the weaving machinery during the manufacture of this Fourdrinier wire cloth results in rough or imperfect Fourdrinier cloth and the objections noted above.

Therefore, it is the particular object of this invention to provide means for positively and accurately actuating the heddle frames, thus preventing any looseness or irregularities in the displacement of the heddle frames, which would affect the quality or finish of the product of the weaving machinery.

Another object of the invention is to provide a gearing wherein the relative positions of the wire sheds, as controlled by the heddle frames is equalized with respect to the supply of warp wires fed to the heddle frames, and also with respect to the distance between the two frames.

The details of construction of this invention will be made more apparent as this description proceeds, especially when considered in connection with the accompanying drawings, wherein;

Figure 1 is a longitudinal sectional view through a portion of a weaving machine, illustrating in section the heddle frame and a portion of the operating gearing;

Fig. 2 is a sectional view taken in a different vertical plane, illustrating the operating gearing for the main shaft; and

Fig. 3 is a fragmentary sectional view, partly in elevation, of the main shaft.

Referring now particularly to the draw-

ings wherein like reference characters indicate like parts, it will be noted that there is illustrated a pair of heddle frames 10 and 11, these being the front and rear heddle frames respectively. The frames are customarily rectangular in form and carry a plurality of perforated steel strips 12, through which wires 13 and 14 pass. In practice these perforated strips 12 are arranged approximately 60 to 100 to the inch, the wires, 13 and 14, passing therethrough, warping the steel strips slightly, so as not to materially affect the alignment of the wires.

The heddle frames are reciprocally supported by means of chains 15, which extend from opposite sides over a pair of wheels, 16 and 17, both rigidly fixed on a shaft 18, so as to turn together, the shaft being mounted in a supporting frame 19. Thus, during the reciprocatory movement of the heddle frames, one of the frames moves upwardly, while the other downwardly, and vice versa. During the reciprocation of the heddle frames, the one supported upon the wheel 16 enjoys a movement greater than that supported upon the wheel 17, and thus the wheel 16 is of a larger diameter than the wheel 17.

Associated with each heddle frame is a rack, these racks being indicated by the reference characters 20 and 21, each being connected to its respective heddle frame by means of a connecting member including a turn buckle 22, so that proper adjustment may be made to compensate for wear of the rack and its associated pinion.

Arranged transversely of the racks 20 and 21 is a main shaft 23, this shaft having fixed thereto, pinions 24 and 25 of different diameters, the pinion 24 being preferably larger than the pinion 25 and meshing with the rack 20, while the pinion 25 meshes with the rack 21. During the operation of the device, the shaft 23 is oscillated and consequently during this oscillation, by reason of the connection between the racks 21 and the shaft 23 by means of the pinions 24 and 25, the heddle frames 10 and 11 are reciprocated simultaneously in opposite directions and to unequal degrees.

Arranged in a different vertical plane on the shaft 23 is a pinion 26, which is adapted to mesh with a pair of racks 27, (see Fig. 2), which are suitably connected to operating levers 28, the connection be-

tween the racks 27 and levers 28 including turn buckles 29, being so that proper adjustment between the levers and racks may be accomplished. An operating shaft 30, 5 is provided with a pair of oppositely extending cams 31, which, upon rotation of the shaft 30 alternately engage the levers 28, rocking these levers on a supporting shaft 32. When the levers 28 are rocked 10 the racks 27 will be reciprocated simultaneously in opposite directions, whereupon the shaft 23 will be oscillated. The reciprocatory movement of the shaft 23, will, in turn, be transmitted to the racks 20 and 21, 15 through the unequal gears 24 and 25, whereupon, as mentioned hereinbefore the heddle frames, 10 and 11, will be reciprocated, the heddle frame 10 receiving the greater reciprocation, due to the larger gear 24. 20 The unequal movement of the heddle frames compensates first for the distance apart of the two frames, and also for the angle of feed of the warp wires, which in practice are fed to the heddle frames from 25 a point slightly above said frames and inclined downwardly thereto. Thus in order to preserve the relative distance apart of the wires, the frame 10 actuated by the larger gear, is moved upwardly and downwardly a greater distance than the other frame, with the result that the wires at the point 33 where the shuttle is inserted, are substantially in the position they would 30 occupy if the feed wires were in alignment horizontally with the center portions of the heddle frames. 35

From the foregoing it will be immediately apparent that a simple, compact and positive and accurate gearing is provided 40 for actuating the heddle frames, due regard being taken of conditions which might affect the quality and evenness of the product produced by the weaving machinery, these conditions being properly compensated for so that a possibility of imperfect or uneven product is eliminated. The gearing is so interconnected as to eliminate the 45 possibility of any looseness of connections which would in a like manner affect the

product of the weaving machinery. The 50 turn buckles associated with the various connections provide suitable means for maintaining the gearing in accurate adjustment.

While an embodiment of the invention 55 has been illustrated herein in some detail, it is not intended that the invention be unnecessarily limited but reservation is made to make such changes in the details of construction and arrangement of parts as may 60 come within the purview of the accompanying claims.

Having thus described the invention, what is claimed is:

1. A heddle frame gearing comprising 65 heddle frames, racks secured to said heddle frames, a shaft provided with pinions of unequal size meshing with said racks, a pair of reciprocating racks, a pinion on said shaft, meshing with said racks, and cam and 70 lever means for reciprocating said last mentioned racks.

2. An equalizing gearing for heddle frames of weaving machines, comprising 75 heddle frames reciprocally supported, racks fixed to said heddle frames, a shaft, a pair of pinions of unequal size on said shaft and meshing with said racks, a pair of reciprocating racks, a pinion on said shaft meshing 80 with said last named racks and cam and lever means for reciprocating said last named racks to oscillate said shaft.

3. An equalizing gearing for heddle frames of weaving machines, comprising 85 heddle frames reciprocally supported, racks fixed to said heddle frames, a shaft, a pair of pinions of unequal size on said shaft and meshing with said racks, a pair of reciprocating racks, a pinion on said shaft meshing 90 with said last named racks and means for actuating said racks whereby said shaft will be oscillated and said heddle frames reciprocated to unequal degrees, for the purpose described.

In testimony whereof, I affix my signature. 95

JOHN D. WATSON.
